UNITED STATES PATENT OFFICE.

LERoy C. BROUgh, OF PERU, INDIANA.

DESIGN FOR A GARMENT HOOK OR RACK.

SPECIFICATION forming part of Design No. 29,729, dated November 29, 1898.

Application filed November 4, 1898. Serial No. 695,513. Term of patent 7 years.

To all whom it may concern:

Be it known that I, LEROY C. BROUgh, a citizen of the United States, residing at Peru, in the county of Miami and State of Indiana, have invented and produced a new and original Design for a Combined Garment Rack or Hook, of which the following is a specification.

The accompanying drawing illustrates my design for a garment hook or rack, the figure being a perspective view thereof.

The design consists of a plate 1, from which projects an arm 2. Extending from the outer end of arm 2 and substantially in line therewith is a finger 3. Rising from the upper side

of arm 2, near the root of finger 3, is an upwardly-extending finger 4, the upper end of which carries a head 5. Depending from the lower side of arm 2 is a finger 6, the lower end of which carries a curved arm 7, which lies in a plane substantially parallel with the plate 1.

I claim as my invention and production—

The design for a garment hook or rack, substantially as shown and described.

LERoy C. BROUgh.
